CLAIM

The ornamental design for a adhesive-backed temporary tattoo cover made of flexible material as shown and described.

DESCRIPTION

FIG. 1 is a top plan view of a flexible, adhesive-backed temporary tattoo cover;

FIG. 2 is a bottom plan view of the temporary tattoo cover of FIG. 1;

FIG. 3 is a left side elevation view of the temporary tattoo cover of FIG. 1, the right side elevational view being identical to FIG. 3;

FIG. 4 is a front elevational view of the temporary tattoo cover of FIG. 1, the back elevational view being identical to FIG. 4; and,

FIG. 5 is a perspective view of the temporary tattoo cover of FIG. 1.

The oblique shading lines indicate transparent surfaces, and the stippling indicates transparent adhesive located on the bottom surface of the temporary tattoo cover.
